UNITED STATES PATENT OFFICE.

GEORGE PARKINSON AND JOHN DAVIDSON, OF CALGARY, ALBERTA, CANADA.

VALVE.

1,401,637.

Specification of Letters Patent. Patented Dec. 27, 1921.

Application filed August 28, 1920. Serial No. 406,656.

To all whom it may concern:

Be it known that we, GEORGE PARKINSON and JOHN DAVIDSON, subjects of the King of Great Britain, and residing in the city 5 of Calgary, in the Province of Alberta, in the Dominion of Canada, have invented a new and useful Valve, of which the following is the specification.

The invention relates to valves, as described in the present specification and illustrated in the accompanying drawings, that form part of the same.

The invention consists essentially of the novel construction and arrangement of parts, 15 whereby the seat may be readily removed and reground.

The objects of the invention are to avoid the expense incident to the removal of the complete casing for repairs to the seat; to 20 facilitate the operation of steam and water installations for heating and all other purposes by avoiding leaky valves; to effect repairs and replacement at a minimum expense and in a short period of time; and 25 generally to provide an efficient, durable and serviceable valve.

In the drawings, Figure 1 is a side elevation of a faucet broken away to disclose the inside of the casing, and the valve and seat.

30 Fig. 2 is an enlarged perspective detail of the valve seat.

Fig. 3 is an enlarged perspective view of the washer under the seat.

Fig. 4 is an enlarged perspective view of 35 the locking screw for the seat.

Fig. 5 is an enlarged perspective view of the washer.

Fig. 6 is an enlarged perspective detail of the nut for the locking screw.

40 Like numerals of reference indicate corresponding parts in the figures illustrating two forms of the invention respectively.

Referring to the drawings, in Fig. 1 a faucet is illustrated in which 1 is the valve 45 casing, 2 the spout and 3 the connection to the water feed pipe.

The partition 4 within the casing 1 represents the customary division between the feed and the spout and is formed with the 50 usual discharge orifice 5 at the edge of which the annular flange 6 projects upwardly as

usual forming what I term a bottom seat, this flange being topped by the washer 7, which in common practice would form the seat below the valve 8 operated by the handle 9 at the end of the stem 10.

The removable or upper seat 11 is mounted on the washer 7 and is suitably ground to meet the valve 8. The seat 11 extends in the form of a ledge over said washer 7 from the body 12, from which projects the V-bar 13 having a locking bolt hole 14 at the juncture of the legs.

The locking bolt 15 having the under beveled head 16 cross slotted at 17 for a driver 65 is inserted through the hole 14 and is threaded for the greater portion of its length, the threaded end 18 projecting through the casing 1 at the lower end and through the washer 19 into the nut 20, which locks the 70 seat firmly in place and at the same time closes the washer 19 tightly around the lower hole in the casing.

In the operation of this invention to replace a seat or to regrind it the valve and 75 cap are removed and the locking screw removed by means of a screw driver and the seat lifted out and subsequently replaced or reinstalled.

It must be understood that variations, in 80 the design and constructional features may occur without departing from the spirit of the invention and that the novel elements are pointed out in the claim following.

What we claim is:

85 A faucet comprising a valve casing having a partition therewithin between inlet and outlet and an orifice in said partition surrounded by a flange having a bottom seat, a double faced removable intermediate seat 90 in the form of a washer and a double faced top seat having a V-shaped bar lower extension and a screw hole at the juncture of the legs of said bar, a bolt having a cross slotted and under beveled head fitting to the 95 slope of said legs and a washer and closed nut secured on the end of said bolt projecting below the valve casing.

Signed at the city of Calgary, Alberta, Canada, this 3 day of August, 1920.

GEORGE PARKINSON.
JOHN DAVIDSON.
